UNITED STATES PATENT OFFICE.

JAMES F. McELROY, OF ALBANY, NEW YORK, ASSIGNOR TO THE CONSOLIDATED CAR-HEATING COMPANY, OF WHEELING, WEST VIRGINIA.

DESIGN FOR AN ELECTRICAL RADIATOR.

SPECIFICATION forming part of Design No. 23,426, dated July 3, 1894.

Application filed May 16, 1894. Serial No. 511,483. Term of patent 14 years.

To all whom it may concern:

Be it known that I, JAMES F. McELROY, a citizen of the United States, residing in the city and county of Albany, State of New York, have invented and produced a new and original Design for Radiators, of which the following is a specification, reference being had to the accompanying drawings, forming a part thereof.

Figure 1 is a front elevation. Fig. 2 is a section, these two views being deemed necessary to fully illustrate my design.

The leading feature of my design consists in a radiator of the shape shown provided with the plate B extending along the front of the radiator, and a series of openings a extending through the plate, together with the plate D curved to form the rear and top of

the radiator presenting a concave surface toward the front of the radiator. The lower 20 edge of the plate B is slightly above the floor.

It will be noticed by the sectional view shown in Fig. 2, that the general design of the radiator is that of a flat vertical surface on one side, a convex surface on the other, 25 together with a narrow flat vertical surface above the convex surface with a cap on the top.

What I claim as my invention, and desire to secure by Letters Patent, is— 30

The design for an electric radiator as herein shown and described.

JAMES F. McELROY.
